TELEVISION RECEIVING APPARATUS

Leslie A. Gould, Bridgeport, Conn., assignor to
Radio Inventions, Inc., New York, N. Y., a cor-
poration of New York

Application October 30, 1931, Serial No. 572,677

6 Claims. (CL. 178—6)

This invention relates to television receiving apparatus and more particularly to the illuminating and scanning parts thereof.

This invention includes means and methods for translating received electrical television signals into optical signals and for so coordinating these optical signals in time and space, as to reconstruct the optical image whose translation into electrical signals at the transmitter gave rise to the received television signals.

In particular, the method of this invention includes scanning received and translated signals by moving in one direction the electro-optical translating device itself, and by moving in another direction some other unidirectional scanning means.

More precisely, this invention includes the method of television reception by moving luminous signal-responsive tubes so as to scan in one dimension, while scanning in the other dimension by other suitable means.

It has for one object to provide a device of this character which will give a larger and clearer picture with greater illumination than can be secured with the devices at present employed, and which will do this with mechanism that requires much less space and is much more simple in construction than the present mechanism.

It is also an object of the invention to provide a device which will give more uniform illumination over the entire picture and will give a larger picture without the loss of illumination that is common at the present time when the common small picture of approximately one inch square is enlarged.

Another object of the invention is to provide a device which will give greater illumination and a brighter picture with less current.

Still another object is to provide a device of this character with which black and white pictures or colored pictures can be received without any change in the apparatus, depending solely on which is sent out at the transmitting station.

A further object is to provide a receiving device in which the picture can be viewed direct or can be projected on a screen.

Still another object is to provide a receiving device with which the images are produced by what is in effect an illuminated line of the desired width and are scanned by means of slots inclined to the illuminated line so that the two together have the effect of moving apertures.

With the foregoing and other objects in view

as will become apparent as the description proceeds, the invention consists in certain novel features of construction, combinations and arrangement of parts as will be more fully disclosed in connection with the accompanying drawings forming a part of this specification, and although certain specific constructions are disclosed, various changes and modifications may be employed without departing from the principles of the invention.

In these drawings:

Fig. 1 is a top plan view showing somewhat diagrammatically the scanning portion of the receiving apparatus showing one form of my invention, the top of the enclosing cabinet being removed.

Fig. 2 is a side elevation thereof, the enclosing cabinet being shown in section.

Fig. 3 is a detail section substantially on line 3—3 of Fig. 1.

Fig. 4 is a wiring diagram of one electrical circuit which may be employed.

Fig. 5 is a wiring diagram showing a different manner of connecting the illuminating elements into circuit.

Fig. 6 is a detail elevation of one form of the scanning device.

Fig. 7 is an end view of a modified form of scanning device.

Fig. 8 is a view thereof looking from the right of Fig. 7.

Fig. 9 is a side elevation of a modified construction of an illuminating element, with parts broken away to show more clearly the construction.

Fig. 10 is an end view thereof.

Fig. 11 is a somewhat diagrammatical side view showing a modified construction of illuminating means.

Fig. 12 is a side elevation of another form of scanning device using my invention.

Fig. 13 is a front elevation of the apparatus of Fig. 12.

Fig. 14 shows schematically the electrical circuit employed with the form of Figs. 12 and 13.

It has been common practice in television receiving apparatus to use as the illuminating element, a neon or similar tube having a plate electrode of approximately one inch square or a little larger. With this type of tube the amount of illumination is limited and it is difficult to illuminate the plate uniformly over its surface, this difficulty often giving a picture which is not uniformly illuminated. Also the size of the resultant picture is limited, because if the image

is thrown on a screen, although the picture is larger, the intensity of illumination is correspondingly decreased, resulting in insufficient illumination on the screen. Also, in this case the 5 projection and enlargement intensify the variation in illumination in different parts of the picture which latter thus becomes more objectionable. In my present invention, I use what is in effect an illuminated line of desired width and 10 preferably secure it either by a plurality of tubes or by a tube so constructed as to give the effect of a plurality of tubes or sources of illumination, and scan these tube structures in producing the picture, thus securing a relatively larger picture 15 with relatively smaller apparatus, as well as a picture which is uniformly illuminated throughout its entire area.

I am able also to secure sufficient illumination so that the picture can be enlarged and 20 thrown on a screen. I prefer to use a gas column type of tube as it gives more uniform illumination, requires less current and responds more quickly to modulation corresponding to the impulses of the received signal, although I am 25 not necessarily limited to gas column type of tubes, but may use electrode type tubes if desired. While I have referred to the illumination as a line, it is to be understood that this does not necessarily mean a line of very narrow width 30 but means a long, relatively narrow illuminated element of any desired width and length.

Referring to Figs. 1 to 6, the illuminated element comprises a rotatable support 12, in the form shown in these figures substantially a drum 35 mounted to rotate on a horizontal axis represented by the supporting shaft 13 running in any suitable bearings 14 in supports 15. Carried by this rotating support or drum is a plurality of tubes 16 preferably of the gas column 40 type such for example as neon tubes which, in the present instance, are shown as being connected in series by leads 17 although they may be connected in any other suitable way as hereininafter described. They may be mounted on and 45 secured to the support by any suitable means such for example as the straps 18. They may be grounded at one end on this support or have a separate collector ring and brush, and at the other end are connected to the modulating apparatus by lead 19, having a brush 20 engaging a ring 21 on the support. The brush 20 and ring 21 of course should be insulated from the frame 50 of the apparatus.

As the support 12 rotates, the lighted tubes carried thereupon may be scanned by a suitable scanning device of which I have shown several different forms. In Figs. 1 to 6, the scanning device comprises a disc 22 mounted to rotate in front of the support 12 and the tubes carried 55 thereby. The tubes may be scanned direct or through a suitable lens 23 mounted between the disc and the rotating support, and the disc may be mounted at any suitable location between the rotating support carrying the lights and the 60 point of observation indicated at 24. The support 12 and the scanning disc 22 are rotated in proper timed relation and in synchronism with the transmitting apparatus by any suitable means such as a synchronous motor 25. In the present 65 instance, the disc 22 is shown as mounted directly on the shaft 26 of the motor, and there is a connection from this shaft indicated generally as a flexible drive 27 for driving the support 12 in certain timed relation with the disc 22, the drive indicated being a worm 28 meshing with a worm 70

gear 29 on the shaft 13. There may be a partition 30 inserted in front of the support 12, having a square or rectangular opening 31 therein corresponding to the size of the picture.

For example, suppose we wished to receive fifteen pictures a second and have 48 lines per picture. Then with the support or drum 12 carrying six tubes 16 as illustrated and rotating 150 R. P. M., it would be necessary for disc 22 to rotate 1800 R. P. M. if it has 24 slots 32. This will give 48 lines for each picture. In other words, with the drum or support 12 rotating at 150 R. P. M. with six tubes we would secure 900 pictures a minute, that is, a picture for each $\frac{1}{6}$ revolution of the drum.

Thus, referring to Fig. 2, a picture will be indicated by the movement of a tube 16 from the position A to the position B in front of aperture 31 corresponding to $\frac{1}{6}$ of a revolution. As the tube passes off the line of vision at the point B, the next succeeding tube has reached the point A which is the beginning of the next picture, so that there is continuous illumination of the 48 lines for scanning or making up the picture. It will, therefore, be necessary that 48 of the slots 32 pass across in front of the drum 12 while each tube is moving from the point A to the point B, or for each $\frac{1}{6}$ revolution of the drum 12. Thus, with 24 slots 32 in the disc, to secure this number of scanning lines for each picture it will be necessary that the disc make two complete revolutions for each $\frac{1}{6}$ revolution of the drum 12, or in the present instance with the drum 12 running at 150 R. P. M. disc 22 with 24 slots runs 1800 R. P. M. Of course, these proportions may be varied as desired with supports carrying greater or less number of tubes or running at greater or less speeds, or with a disc 22 having a different number of slots. Thus, with the same drum 12 and the six tubes as illustrated and running at the same speed, if disc 22 had only 12 slots 32 it would be necessary to run it at twice the speed or 3600 R. P. M. to secure the same number of scanning lines per picture, or if disc 22 had 36 slots 32 it would be necessary to run it only 1200 R. P. M.

It is understood that the foregoing numerical values are merely illustrative of certain possible combinations, and that if a different number of scanning lines and/or pictures per unit time be postulated, these values will become changed in their turn.

A picture is ordinarily scanned from top to bottom and from left to right. That is, the support or drum 12 rotates to the right or clockwise as viewed in Fig. 2 while the disc 22 rotates to the left or counter clockwise as viewed in Fig. 3, or clockwise as viewed from the observer's position at 24, which would carry the slots 32 from left to right across the tubes 16.

It will be apparent from this that the tubes 16 are each in effect an illuminated heavy line extending horizontally and longitudinally of the axis of rotation 13, the width of this line depending on the size of the tubes or the portion of their illuminated surface which is visible. It also will be noted from Fig. 6 that the slots 32 are inclined relative to these illuminated lines or tubes 16, and therefore, a point at which they cross, indicated at 33 in Fig. 6, is in effect an aperture, either rectangular or wedge shaped, which is carried along the full length of the illuminated tube by the movement of the disc 22. This gives greater illumination than is secured with the old type of scanning apparatus using a series of 75

small round apertures. The lines also blend more uniformly and better, giving a more steady and more continuous picture.

With this apparatus I can secure a much larger picture and a much more brilliantly illuminated picture than with the old type of apparatus. Thus, with a 12 inch drum and using tubes with an illuminated part about 6 inches long I can secure fully illuminated pictures about 6 inches square, and with larger drums and longer tubes, I can secure pictures of practically any size desired and the entire picture will be fully and uniformly illuminated. If it is desired to view the picture directly at 24, the lens at 24 may be removed and the lens 23 could be a concave lens (as with a convex the image would appear inverted) or if a convex lens is used at 23 then there could be used a projecting lens at 24 to project an erect image upon a screen. The lenses also tend to concentrate the light rays and make the picture more brilliant. If preferred, the lenses may be omitted and the picture viewed directly.

It will be evident that with the flat disc 22 as one scanning element, it must be of considerable size in order to secure the requisite number of slots, and also as the slots extend radially as indicated in Fig. 6 the picture will be slightly distorted due to the angle of change of these slots, the lines being slightly curved. To reduce the size of the scanning means and make the apparatus more compact and reduce distortion, I can use the scanning device shown in Figs. 7 and 8. In this device, the illuminating tubes 16 are carried on the same type of support or drum 12, but the scanning element is a second drum 34 surrounding the first drum and the light tubes mounted thereon.

This scanning drum has a series of inclined slots 35 which are carried across the light tubes 40 in the scanning operation. That is, with the drum rotating clockwise as viewed in Fig. 7, the scanning drum 34 will rotate counter clockwise, i. e., in the opposite direction, and the slots 35 are so inclined that they will scan the tubes from left to right. Thus, as the left hand and upper end 36 of a slot moves onto the left hand end of the illuminated portion 38 of the tube 16 as indicated by the dot and dash lines in Fig. 8 the right hand end 39 of the next upper slot has just moved off the right hand end of the illuminated portion so that they do not overlap but accurately blend into each other. If this drum 34 has 24 slots it may be rotated at 1800 R. P. M. if the drum 12 is rotated at 150 R. P. M. That is 55 in the same ratio as indicated for the disc 22 above, and variations in the speed of the drum, number of lights and number of slots will call for similar variations to correspond as described in connection with the disc 22. The drums 12 and 34 are driven in certain timed relation with each other and in synchronism with the transmitting apparatus. Various driving mechanisms may be used as desired. Thus, if the worm 28, Fig. 8, is driven directly from the motor drive and meshes with the gear 29 on the shaft 13 for the drum 12 and the drum is thus driven 150 R. P. M., suitable step-up gearing may be employed to drive the drum 34 at the proper speed. Thus, a large gear 40 may be mounted on the shaft 13 and 60 through certain sized gearing as a smaller pinion 41 on a counter shaft 42 and through other gearing 43, 44 and 45 may drive the drum 34 at the proper speed, the gear 45 being connected to this drum. Or, if preferred, the drum 34 may be 65 driven directly from the motor armature shaft

and the drum 12 may be driven from it by reducing gear.

In the form of device shown in Figs. 1 to 8, the illuminating elements 16 are separate tubes mounted on the rotating support or drum and electrically connected together. However, a single tube may be used if preferred, as indicated in Figs. 9 and 10. In this form of device, the drum 46 corresponds to the drum 12 in the first form and the single tube 47 is bent in zigzag form 10 back and forth and mounted on the drum. The end flanges 48 may have suitably shaped recesses 49 to receive the connecting portions 50 of the tube between the horizontal or illuminated portions 51. The tubes may then be secured in these 15 recesses and all except the proper length of horizontal portions 51 covered by means of hoops or rings 52. This provides a series of spaced horizontal illuminated portions 51 corresponding to the spaced tubes 16 of the first form giving the 20 same effect in both instances so that where spaced tubes are mentioned in the claims, this is intended to cover either arrangement. The tube 47 of 25 Figs. 9 and 10 may be lighted in the same manner as that in Fig. 1 except that one end of the tube may be grounded and the other connected by lead 53 to the insulated disc 21 cooperating with the brush 20 connected to the modulating apparatus as in the first form.

It will be apparent that as the tubes travel 30 from point A to point B, which is the scanning portion of a revolution, they move in a slight curve and produce a slightly curved field in the resulting picture, but it is so slight as to be non-objective. However, a perfectly flat field 35 may be secured by mounting the tubes on a flexible belt 54 running over pulleys or drums 54' as indicated in Fig. 11, the tubes being scanned while on one of the straight sections of the belt.

Of course, the intensity of illumination of the 40 gas column type of tubes 16 and 51 is modulated according to the impulses received. In Fig. 4, I have shown diagrammatically a wiring layout in which 55 is the tube of the last stage of the audio amplifier of any receiving set and the plate 45 output leads through a radio frequency choke coil 56 to an oscillator 57 which may be of the 250 or 210 type tube and whose output energizes the tubes 16. I prefer to use a high frequency oscillator for energizing the tubes as the tubes are 50 energized with less voltage when such high frequency current is employed. Also the oscillator is an amplifier as well as an oscillator, so that it increases amplification of the signals. In this type of tubes the gas column glows, as distinguished from the plate type of gas tube in which the plate glows. The tubes are also cheaper to make, as no glowing electrodes are required in the tubes. The tubes may be connected to any suitable regeneration control 58, and current may 60 be supplied to the filament of the tube 57 by any suitable type of filament transformer 59. The connection shown in Fig. 4 is known as the Heising system of modulating, but, of course, other systems of modulating could be used, such for 65 instance as where the grid is modulated instead of the plate as in Fig. 4. Likewise the tubes 16 may be connected directly to the output of the amplifier of the receiving apparatus as shown in Fig. 5 where 55 is the last audio tube of the receiving set.

All of the tubes 16 or 51 can be of the same color if desired, but by using differently colored tubes we can receive colored pictures in this apparatus provided the broadcast is, for example, 75

from films taken through correspondingly colored screens or shutters. Thus, for example, each alternate tube 16 may be red and the remaining tubes green, these being two primary colors, and if the broadcast is from films in which every alternate picture is through a red screen and the others through a green, then the pictures received by this apparatus will be correspondingly colored. However, if the broadcast pictures are black line pictures, the received pictures will also be black line pictures. Thus, with the apparatus having alternately differently colored lamps, we can receive either black line pictures or colored pictures without changing the apparatus in any way, depending solely on whether black line or colored pictures are being broadcast from the sending station. Likewise the object at the sending station may be scanned directly and red and green lights alternately flashed upon it, or the light from the image may be passed alternately through red and green shutters for the alternate pictures. This device, of course, is not limited to two colors as red and green, as three different colors such as blue, yellow and red may be used in the same manner. This device may be used with either system of scanning the object, that is either where the scanning disc breaks into lines the light reflected from the object or where the disc projects as lines the illumination from the light source. That is, in one system the object is subjected to full lighting of high intensity, while in the other it is rapidly scanned by a pencil of light.

It will be evident from the foregoing description that this system is a very simple one requiring very simple mechanism, and that much larger pictures with more intense and uniform illumination can be secured with much smaller apparatus than in the old type of devices. As the rotating members are much smaller, there is much less vibration due to the required speed of rotation and there are much smaller centrifugal forces to overcome and control. The combination of the strip of light or line of light of a given width produced by the illuminated tube with the inclined slots in the scanning elements gives the effect of apertures, and because of their relation much more light can be transmitted and these apertures all blend one into the other as they move across the illuminated elements. Of course, the intensity through this resulting aperture is modulated by the radio receiving apparatus according to the impulses received from the transmitting station. This modulation, that is, increased or decreased intensity of illumination of the tubes according to the signals received gives the effect of the relatively light and dark lines in the pictures, that is, the lines of varying intensity produce the effect of the picture. With this apparatus the size of the picture received may be very great if desired. For example, by using a two-foot drum 12 carrying illuminating elements with corresponding increase in size of the scanning element we can secure a picture one foot square and having the same relative intensity of illumination as a smaller picture.

In the form of device shown in Figs. 12 to 14, the illuminating elements are separate tubes 66 with terminals 68 mounted on a rotating support or drum and electrically connected together at one end through the common agency of a slip ring 61, upon which bears a brush 61' connected to the high potential terminal of the high frequency circuit. If the illuminated tubes are to be operated from a circuit similar to that of Fig. 4,

said tubes are preferably not conductively connected to any circuit or to one another at the other ends, but are each effectively connected, by means of their electrical capacity, to the end plate 62 of the drum, said end plate being connected to the low-potential terminal of the high-frequency circuit. End plate 62 should then be of a conducting material and the other end plate 63 may be of an insulating material.

The equivalent circuit of the tubes, slip ring, and end plate 62 is shown in Fig. 14, and the combination may be inserted in the circuit of Fig. 4 in place of the tubes and series capacity there shown.

This constitutes parallel excitation of branch circuits each comprising one tube and a series capacity, in distinction from the single series circuit of Fig. 4.

Tubes 66 may be supported in V-grooves 64 cut in the periphery of end plates 62 and 63, by means of spring wire clips 65 attached to said end plates and engaging a tube at each side of the point of said attachment.

These tubes may also derive their excitation current through a suitable capacitative type of slip ring. That is instead of the brush actually bearing upon the slip ring, it can be of suitable size to afford sufficient capacity by its proximity to the ring.

The line-scanning device in this form of the apparatus comprises a drum 66 in which a plurality of longitudinal slits 67 are cut, preferably with beveled edges. The axis of said drum may be at a considerable angle or perpendicular to the axis of tubes 66. A stationary mirror 68 may be supported within drum 66 by means of bracket 69 and serves as the medium in which the image is viewed. The length of slits 67 may be approximately equal to the spacing of tubes 66 and will normally determine the apparent height of the image, while the circumferential spacing of said slits will normally determine the apparent width of said image. For direct viewing, a cylindrical convex lens 70 may be placed before mirror 68 with its axis parallel to the height of the image, in which case the circumferential spacing of slits 67 may be decreased in the proportion of the horizontal magnification provided by lens 70. The horizontal edges of this lens may be fixed in channel frames 70'. The use of this optical system allows a smaller diameter of drum 66, other things remaining equal.

An external framing stop 71 with viewing aperture 72 may be provided to limit the visible image to slightly more than a single complete picture. Horizontal movement of the lens 70 and its frames 70' upon guides 73 and 74 may be allowed, in which case the image may be centered in the horizontal direction by moving said lens and its frames along the guides as by means of a handle 75 attached to lower frame 70'.

A friction clutch member such as a friction disc 76 attached to end plate 62 and engaging friction disc 77 which is rotatable on shaft 78 and is driven from the body of sprocket 79 (also rotatable on shaft 78) by means of a helical spring 80, may be provided to rotate the drum carrying tubes 66. In this case a brake shoe 81 actuated by lever 82 and acting on slip ring 61 may be used to frame the image vertically 70 by causing an angular "slip" in the rotation of said drum when the brake is applied.

Sprocket 79 may be rotated by means of a motor 84 through the agency of a worm 85 fixed on shaft 86 of said motor, gear 87 cooperating with 75

said worm and fixed on counter-shaft 88 which is supported in proper bearings, sprocket 89 also being fixed on said counter-shaft, and chain 90 engaging sprockets 89 and 79. Drum 66 may be mounted directly on shaft 86 of motor 84 and rotated thereby.

5 The form of my invention illustrated by Figs. 12, 13, and 14 is free from the shape-distortion of the elementary optical area, which takes place 10 when the two scanning members do not optically intersect so as to produce a true rectangle. The slotted drum of this type often presents mechanical advantages in regard to its construction and operation, in comparison with a slotted disc. 15 The parallel connection of the tubes in this form, allows a more suitable effective load to be obtained for a simple oscillator, employing relatively low anode potentials. The impedance in series with each tube allows a more uniform illumination when the individual tubes are of differing characteristics, and the net resultant capacity of the whole can be made resonant with the inductance feeding it, for maximum efficiency.

I claim:

- 25 1. In television receiving apparatus, a rotatable support, illuminating elements comprising a plurality of spaced gas column type tubes on said support, the alternate tubes being of different colors, means for modulating the illumination of said tubes, and a scanning means 30 associated with said support.
2. In a television receiving apparatus, a rotatable support, a plurality of spaced light producing elements of substantially rectangular shape and uniform width mounted on said support and extending longitudinally of its axis of rotation, the alternate elements being of different colors, means for modulating the illuminating intensity of said elements, a slotted scanning member rotatable relative to said support, and means for rotating the support and scanning member in certain timed relation to each other so that at least one of said light producing elements is visible at all times.
- 35 40 45 3. A television receiver including a plurality of light producing elements in substantially linear form, means for moving said elements so

as to scan in one dimension, optical refractive means receiving the light from said light producing elements, means for scanning in the other direction receiving the light from said optical refractive means, and optical refractive means receiving the light from said second scanning means.

4. A television scanner including a colored light source reproducing television signals, means for moving said source so that it traverses at least one dimension of the scanning field, a second differently colored light source also reproducing television signals, means for causing said second source to enter said scanning field after said first source has left said field and to traverse at least one dimension of said field, said light sources all traversing substantially identical physical paths during their movement across said field, said light sources acting to scan said field in one dimension by their respective movements thereacross, and also including separate means for scanning said field in the other dimension, operative cojointly with said light source scanning means so as to accomplish substantially complete scanning of said field.

5. In television receiving apparatus, a rotatable support, a plurality of illuminated elements in substantially linear form and mounted on said support, alternate illuminated elements being of different colors, means for modulating the illumination of said illuminated elements, and a scanning means associated with said support.

6. In a television receiving apparatus, a rotatable support, a plurality of spaced light producing elements of substantially linear form mounted on said support, extending longitudinally of its axis of rotation and operating so as to project an illuminated field, means for modulating the light produced by said elements, a slotted scanning member rotatable relative to said support, means for rotating the support and the scanning member in certain timed relation to one another and a substantially cylindrical lens increasing the apparent distance apart of the slots in said scanning member.

LESLIE A. GOULD.
